SPIRIT LEVEL CASING

Filed Nov. 29, 1947

UNITED STATES PATENT OFFICE

2,543,139

SPIRIT LEVEL CASING

William Veit, Bronx, N. Y.

Application November 29, 1947, Serial No. 788,837

1 Claim. (Cl. 33—207)

1

This invention relates to spirit levels consisting of a spirit and air bubble tube mounted in a casing.

It is the principal object of the invention to provide a spirit and air bubble tube carrying casing arranged to be releasably attached to either a horizontally or vertically extending element to be leveled without the necessity of providing more than one spirit and air bubble tube in said casing.

Other objects and advantages of this invention will be disclosed in the detailed description of the invention.

In the drawing accompanying and forming a part of this application, Figure 1 is a top plan view of the spirit level constituting the embodiment of the invention.

Figure 2 is a longitudinal sectional view taken on the line 2—2 of Figure 1 looking in the direction of the arrows.

Figure 3 is an end view looking at the left hand side of Figure 1.

Figure 4 is a view of the spirit level detachably engaged on a drill press shank to show the application of said level to a vertically extending element.

Figure 5 is a view of the spirit level detachably engaged on a planer to show the application of said level to a horizontally extending element.

Figure 6 is a view showing the level attached to an arm of the user to facilitate leveling of different elements or tools being handled.

Figure 7 is a fragmentary top view, on an enlarged scale, of a pivotal mounting of one end of a resilient and flexible band on the casing of the level.

Figure 8 is a side view looking at the bottom of Figure 7.

Figure 9 is an end view looking at the right hand side of Figure 8 with part of the casing in section.

Figure 10 is a view similar to Figure 9 of a modified form of mounting of the ends of the resilient band on the casing of the level.

Figure 11 is a sectional view taken on the line 11—11 of Figure 10 looking in the direction of the arrows.

In carrying out the embodiment of the invention illustrated in the accompanying drawing, there is provided a casing formed from a metal bar 12 of square form in cross section or of other suitable material having a longitudinal chamber 13. The chamber may be formed in the bar or casing by a bore extending through one end to adjacent the opposite end and parallelly of the

2

longitudinal axis of the casing and adjacent to a longitudinal face thereof. Said longitudinal face of the casing is provided with a sight opening 14 opening to the chamber 13.

5 A spirit and air bubble tube 15 is engaged in the chamber 13 through the open end of the chamber with the bubble exposed through the sight opening 14 when the casing is positioned with the sight opening uppermost. The tube is retained against movement in the chamber 13 by a plug 16 engaged in the open end of the chamber to abut one end of the tube with the opposite end of the tube abutting the closed end of the chamber, as shown in Figure 2.

10 15 The longitudinal face of the casing opposite the longitudinal face arranged with the sight opening 14 is provided with a groove 17 extending longitudinally of said face and shown as being of arcuate shape in cross section with a straight wall portion 17' on each side of the groove, as shown in Figure 3. The opposite ends of the casing 12 are arranged with corresponding grooves 18 extending parallelly of said ends and each other with a straight wall portion 18' 20 25 on each side of each of said grooves, as shown in Figure 1.

The grooves 17 and 18 permit the engagement of the casing 12 on the element to be leveled. The casing is releasably retained on said element by a flexible and resilient band shown in the present illustration as comprising a helical flat band 19 of spring metal in the form of an extension spring having the opposite end portions extending from the longitudinal center of the band and arranged 30 35 in the form of eyelets 20. The opposite ends of the band 19 are pivotally connected to the opposite sides of the casing midway of the longitudinal faces and the ends of the casing by engaging the eyelets 20 on a conical face 21 of a head 22 of a pin 23 secured in each of the sides of the casing midway of the longitudinal faces and the ends of the casing, as shown in Figures 1, and 3 to 9, inclusive. The pivotal mounting of the eyelets 20 on the conical faces 21 permit the positioning of the band 19 to extend in a plane longitudinally of the casing, as shown in Figure 4, or to extend in a plane transversely of the casing, as shown in Figures 1, 2, 5 and 6.

45 In Figures 10 and 11, there is shown a modified form of the pivotal mounting of the band 19 on the casing 12, wherein the opposite end portions of the band are of rod formation shaped to hook form, as shown at 24. The hook end portions 24 are pivotally engaged in a transverse opening 25 50 55 in a head 26 of a pin 27 secured in each of the

sides of the casing midway of the longitudinal faces and the ends of the casing. The diameter of the openings 25 is greater than the diameter of the hook end portions 24 to permit pivotal movements of said hook end portions in the heads 26 about transverse axes of said heads and positioning of the band 19 to extend in planes longitudinally and transversely of the casing 12.

Figure 4 shows the application of the device to level a vertically extending element, such as a drill press shank 28 of round shape in cross section, by engaging the straight wall portions 18' of one of the grooved ends 18 with the shank 28 and the band 19 encircling the shank to retain the straight wall portions 18' in engagement with the shank and the casing 12 extending perpendicularly of the shank.

Figure 5 shows the device applied to a horizontally extending element, such as a planer consisting of a cutting element 29 carried by a tubular frame member 30. The straight wall portions 17' of the casing are engaged on the tubular frame member 30 with the band 19 encircling said member and retaining said straight wall portions in engagement with the member and the casing 12 extending parallelly of said member.

Figure 6 shows the device applied to a forearm 31 of a user of the device, whereby the user may readily ascertain whether an element or tool he is handling is level.

The grooves 17 and 18 may be of any other suitable cross sectional shape, such as square or hexagonal, depending upon the cross sectional shape of the element to be leveled.

The grooves 17 and 18, and the pivotal mounting of the head 19 permit the leveling of vertically or horizontally extending elements without requiring the mounting of more than one spirit and air bubble tube in the casing.

Having thus described my invention, I claim:

In a spirit level, a casing in the form of a bar of square shape in cross section having a chamber extending longitudinally thereof and a sight opening in one face communicating with the chamber, a groove in and extending longitudinally of the opposite face, and a corresponding groove in each of the ends of the casing extending parallelly of each other and at right angles to the faces, a spirit and air bubble tube mounted in the chamber to extend in the direction and parallelly of the faces with the bubble exposed through the sight opening in the casing, and a flexible and resilient band pivotally connected at the opposite ends to the opposite sides midway of the ends of the casing to detachably mount the casing on an element to be leveled with a groove of the casing spanning said element.

WILLIAM VEIT.
